Fig. 1

Fig. 3

Fig. 2

FIG. 1 is a front perspective view of a hospital bedside service console showing our new design;

FIG. 2 is an enlarged fragmentary bottom plan view thereof; and

FIG. 3 is a fragmentary front elevation thereof.

For the purpose of the present design, the back and the upper end of the console are considered as planar, the constructional and utilitarian aspects of the back and top portions forming no part of this invention. The two side members of the console are mirror images of one another.

We claim:

The ornamental design for a hospital bedside service console, as shown and described.
